UNITED STATES PATENT OFFICE.

JOHN C. SHEFFNER, OF ELGIN, ILLINOIS.

SECTIONAL PARTITION.

Application filed January 12, 1923. Serial No. 612,251.

To all whom it may concern:

Be it known that I, JOHN C. SHEFFNER, a citizen of the United States, residing at Elgin, in the county of Du Page and State of Illinois, have invented certain new and useful Improvements in Sectional Partitions, of which the following is a specification.

This invention relates in general to sectional constructions assembled from a plurality of individual units, and while the invention is illustrated herein as embodied in a partition structure adapted to be used in packing cases and the like, the invention is not limited to such embodiment, but is capable of a wide variety of uses.

One of the primary purposes of my invention is to provide a series of duplicate units which may be economically manufactured in large quantities and shipped in knocked down condition so as to occupy a minimum amount of space and which can be quickly and easily assembled by the user into a unitary structure of any desired size, the units being adapted to be firmly interlocked one with another to provide a strong rigid and durable structure adapted to satisfactorily serve for a long period of time.

For the purpose of facilitating an understanding of my invention, I have illustrated in the accompanying drawings, one preferred embodiment thereof from an inspection of which, when considered in connection with the accompanying drawing, my invention and many of its inherent advantages should be readily understood and appreciated.

Referring to the drawings

Fig. 1 is a horizontal sectional view, illustrating a fragment of a packing case equipped with my invention;

Fig. 2 is a vertical sectional view through the structure, shown in Fig. 1;

Fig. 3 is an enlarged plan view of one of the joints connecting the units of the structure;

Fig. 4 is a detail of one end of one of the units; and

Fig. 5 is a view similar to Fig. 3, showing another method of locking the units together.

On the drawings, reference characters 6 and 7 indicate two adjoining side walls of a packing case or the like, which may be of any preferred construction. This case is illustrated as divided into a series of com-

partments by a partition structure embodying my invention. The particular partition structure illustrated is adapted to divide the case longitudinally and transversely into a series of substantially rectangular compartments, but it should be manifest that the size and shape of the compartments may be widely varied by varying the number of units united at one point and also by varying the shape of the interlocking portions of the respective units. In the form illustrated, the partition is composed of a series of duplicate units 8 provided at one or both ends, depending upon whether they are to be used as end units or intermediate units, with interlocking structures preferably formed from and integral with the metal of the body of each unit.

One of these interlocking structures is shown in Fig. 4, from which it will be observed that the metal of the body near its end is first bent laterally at an angle of substantially forty-five degrees from the plane of the body, as indicated at 9, thence at right angles to provide the portion 11, then at right angles to provide a portion 12 parallel with the portion 9, then again at right angles to provide a portion 13 parallel with the portion 11 and then again at right angles to provide a margin 14 parallel with the portions 9 and 12 and disposed between them. This formation of the metal provides an involute along the edge of the body of the unit, the convolutions of which are disposed at substantially right angles to the adjoining portions thus forming what may be termed an angular involute.

The units thus formed in the factory may be shipped in bundles to users and will occupy a minimum amount of space in transit. The user assembles the units into a structure of the desired size by nesting the interlocking portions, which is accomplished by sliding them together longitudinally, or in other words, in the plane of the body portions. When thus assembled the various convolutions of the interlocking involutes will assume the relative positions shown in Fig. 3, thus providing a joint by which the interengaged units are firmly bound together.

While the joints thus provided prevent longitudinal separation of the various units, I find it preferable, in cases where the partitions are to be repeatedly used and handled, to make provision for locking the joints so that the various involutes may not become

unnested by sliding movement. This result may be accomplished by binding the various interlocking convolutions of the involutes together. One method of effecting this interlocking is illustrated in Fig. 3, from which it will be observed that I have inserted into the opening at the center of the joint a slightly tapered pin 15 which is illustrated as circular in cross-section, although obviously it might be of any polygonal shape. The insertion of this pin or rod spreads the inner convolutions and imposes a frictional resistance between the various involutes which securely locks them together.

15 Another method of effecting the interlocking is illustrated in Fig. 5. In this method the outer convolutions are bent slightly inwardly as indicated by reference character 16 on one or more sides of the joints, thereby binding the various involutes together against relative movement. It will be apparent that when the units have been assembled and interlocked in the manner described a strong rigid and durable partition construction is produced which may be handled and repeatedly used without danger of displacement or separation of the units from each other.

It should be understood that the various units may be of any desired depth, and where it may be desirable to divide the packing case horizontally, as well as vertically, the depth of the units is substantially one-half, one-third or any desired fraction of the total depth of the case and each partition structure is separated from those above or beneath, as the case may be, by horizontally disposed partitions 17 in the form of a board, sheet of metal or other preferred structure as illustrated in Fig. 2. In this figure the top of the case is indicated by reference character 18.

It will be apparent from the foregoing that I have provided a partition structure composed of structurally independent units which are assembled and interlocked so as to produce a strong, durable and rigid structure. It should also be manifest that the

invention may be embodied in forms differing materially from that illustrated without departing from the spirit of the invention as defined in the following claims.

I claim:

1. A partition, comprising a plurality of structurally duplicate units provided with interengaged involutes, whereby said units are interlocked.
2. A partition, comprising a plurality of duplicate units, shaped to provide along the edge thereof rectangular involutes adapted to be engaged to lock said units together.
3. A partition, comprising a plurality of units connected together by rectangular duplicate interengaged involutes, said involutes being distorted after interengagement to prevent disengagement thereof.
4. A partition, comprising a plurality of units provided with similarly shaped and proportioned rectangular involutes adapted to be interengaged to form a unitary structure.
5. A unit of the character described, comprising a flat body provided at an end thereof with an angular involute intersected by the plane of said body.
6. A partition unit, comprising a body portion formed along one edge to provide an involute adapted to be interlockingly engaged with a plurality of similarly shaped involutes of duplicate units.
7. A sheet metal partition unit, having an edge thereof bent to form an angular involute adapted to be interlockingly engaged, upon edgewise movement of the unit, with identically shaped involutes of duplicate units.
8. A partition structure, comprising a plurality of units each comprising a body portion provided with an angular involute to interengage with similar involutes of duplicate units whereby said units are connected together to form a partition structure in which the units radiate in a plurality of planes from the joint produced by the interlocked involutes.

JOHN C. SHEFFNER.
